UNITED STATES PATENT OFFICE.

CARL BUSCH THORNE, OF HAWKESBURY, ONTARIO, CANADA.

LOG-BARKER AND THE LIKE.

15,144.

Specification of Reissued Letters Patent. Reissued July 5, 1921.

Original No. 1,319,935, dated October 28, 1919, Serial No. 286,138, filed March 29, 1919. Application for reissue filed March 29, 1921. Serial No. 456,661.

To all whom it may concern:

Be it known that I, CARL BUSCH THORNE, a subject of the King of Norway, residing at Hawkesbury, in the Province of Ontario, 5 Dominion of Canada, have invented a new and useful Improvement in Log-Barkers and the like, of which the following is a specification.

The invention relates to log barkers and 10 the like as described in the present specification and illustrated in the accompanying drawings that form part of the same.

The invention consists essentially of the 15 novel construction and arrangement of parts, whereby the logs are maintained continuously and variously in rolling contact by circulating them regularly in their progress through the machine.

The objects of the invention are to re- 20 move the bark from logs of any length without injury to the log or waste of good wood; to simplify the methods of handling logs in barking operations; to efficiently strip the bark notwithstanding adverse cli- 25 matic conditions; to economize in labor and power; and generally to provide a serviceable and durable machine at a moderate cost for barking, clearing logs of ice and washing logs and for any other use in which 30 rubbing action is desirable.

In the drawings, Figure 1 is a side elevation of the machine showing hopper sides removed to disclose the movement of the logs in their circulation.

35 Fig. 2 is a plan view of the machine.

Fig. 3 is a detail of a cam.

Fig. 4 is an elevation of the machine at the delivery end.

40 Fig. 5 is an elevation of the machine at the feeding end.

Fig. 6 is a detail of a hopper showing another mechanism for creating the circulatory movement of the logs.

45 Fig. 7 is a detail of a hopper showing another modification.

Fig. 8 is a detail of a hopper showing another modification.

Fig. 9 is a detail of a hopper showing another modification.

50 Fig. 10 is a detail of a hopper showing another modification.

Fig. 11 is a plan view showing an alternative drive and the corresponding positions of the displacing cams.

Fig. 12 is a detail of a hopper showing a 55 preferred form of rear wall.

Fig. 13 is a plan view of the bark draining trough and conveyer.

Like numerals of reference indicate cor- 60 responding parts in each figure.

Referring to the drawings, the numerals 1, 2 and 3 indicate hoppers having the curved and sloping front walls 4 terminating at the side walls 5 and the lower ends of the said front walls forming bottom por- 65 tions for the hoppers and meeting the rear walls 6 which extend upwardly to the top of the side walls in a plurality of inclined sections. The lower and greater inclined sections 7 of the rear walls and the lower 70 curved sloping portions of the front walls form the bottoms of the hoppers. The lower inclined sections or bottom portions 7 are provided with cam slots 8 and 9 which regis- 75 ter with corresponding slots in lateral por- tions of the front walls 4 and each pair of registering slots forming a single continuous opening or slot extending across the bottom of the hoppers from front to rear.

The said hoppers are made in any suitable 80 number, in some cases only one is necessary, while in others the number of hoppers de- 85 pends on the condition of the bark and con-sequently the difficulties it offers toward re- 90 moval. These hoppers are preferably lined with boiler plate and constructed of tim- 95 bers, steel or concrete and supported by the structure here shown in the vertical beams 10 and the longitudinal girders 11.

The said structure supports at the feed end 90 the platform 12, which continues to the in- 95 clined way 13 and this leads into the hop- 100 per 1.

The inclined platform 14 is the connection between hopper 1 and hopper 2 and the in- 95 clined platform 15 is the connection be- 105 tween hoppers 2 and 3.

The runway 16 is the delivery platform and leads from the top of the rear wall of the hopper 3 and terminates the path of the 100 log through the machine starting from the feed platform 12.

The endless chain carrier 17 carries the 105 log along the platform 12 up to the inclined way 13.

The sprocket wheels 18 and 19 are jour- 110 naled in suitable bearings supported by the structure and carry the chain 17.

The structure supporting the hoppers and operating machinery is constructed on the concrete bed 20. The bearings 21 are supported above the bed 20 and from the longitudinal girders and line up with the cam shaft bearings 22 secured to the hopper structure adjacent to the slots 8 and 9.

The cam shafts 23 are journaled in the bearings 21 and 22 and at their outer ends carry 10 the gears 24, which are necessarily of considerable size to insure a regular and comparatively slow rotatory movement to each of said shafts.

The bearings 25 are suitably supported 15 above the concrete bed and the pinion shafts 26 are journaled in said bearings, said shafts 26 carrying the pinions 27 coacting with the gears 24. The pulleys 28 are also fixedly mounted on the pinion shafts 26 and are 20 operatively connected to the motor 29 by the belts 30.

The sprinkler pipes 31 are supported above each hopper and are connected to a suitable water supply.

25 The cams 32 are mounted on the cam shafts 23 and in turning enter the slots 8 and 9, said cams having a receding face 33 and 34 at the ends from the direction of rotation, so that in turning these faces 33 and 30 34 each engage the logs 35 and leave them to drop behind the cams, which are correspondingly recessed at 36 and 37.

The cam openings in the bottoms of the hoppers lead into a drain trough 38, which 35 slopes downwardly in the direction of the delivery end of the machine and receives the water and bark from the hoppers.

At its lower end the trough 38 empties 40 into the transverse trough 39, in which the scraping conveyer 40 operates, said conveyer being formed of the chains 41 carrying the scrapers 42 and turning with the sprockets 43, which are suitably driven. The bottom of the trough 38 is perforated, 45 therefore the water is drained off and the bark conveyed to its delivery point for use as fuel or in the manufacture.

In the operation of this invention, the logs are first directed to the feed carrier and 50 by means of this carrier deposited at or near the inclined way leading into the first hopper.

The logs fall down and as the hopper fills, the cams are covered in, but at each 55 revolution they displace and roll several logs, in fact they continuously make place for the fall of a number of logs, thus creating a disturbance that brings the constantly feeding logs from behind the cams to a position 60 thereabove, where their contact with said cams rolls them around, so that they rub hard against the logs immediately thereabove and at this point the most effective work in the operation is accomplished. 65 The logs gradually work up and around so

that there is a distinct circulation within each hopper, which appears to culminate centrally in each hopper, in the raising of one or more logs to the top from underneath at each stroke and these are usually 70 well barked.

The number of hoppers may or may not depend on the condition of the logs, for it is safe to say, that to add to the number of hoppers means a considerable increase in 75 the rubbing operations and therefore the efficiency is often increased, though on the other hand too many hoppers may injure the wood, therefore under some conditions the rubbing operations in each hopper may 80 be lengthened and this can be done by delaying the feed. This construction materially facilitates the work of the attendant in adjusting operations to insure efficiency 85 under varying conditions.

The main feature of the invention is the making of a hole or creating a space, into which the logs must fall, thereby causing a continuous movement among the logs, in other words, insuring a circulation that will 90 bring every log at time in contact with the disturbing element and impart to said log the desired roll, which has so much to do with removing the bark.

As the disturbance of the logs, preferably 95 at a given point, is essential to the operation of the machine it is obvious that this may be done by other mechanical means than the rotating cams hereinbefore described, as for instance, in Fig. 6, a reciprocatory 100 machine is used in which 44 is a cylinder connected to a suitable supply of expansile fluid and having a piston therein connected with the rod 45 and cross head 46, the latter being connected to the oscillatory rod 47, 105 which operates the pusher 48.

The pusher or pushers, as there may be more than one, engage the logs and accomplish the purpose for which the cams are 110 used.

In Fig. 7 another displacing mechanism is shown and is similar in many ways to the cams described, for it consists of a succession of rotors 49, suitably driven, and having pins 50 or teeth or any projections, 115 which will engage and lift the logs.

In Fig. 8 the toothed chain 51 is shown as extending through a slot in the lower section of the rear wall in a similar manner to the cam and forming the disturbing element and this carries the logs continuously from one corner of the hopper and at its upper ends drops them back into the middle of the hopper where they gradually work back to the carrier again.

In Fig. 9 a plurality of cams 52 triangular in cross section are shown, these being arranged preferably in sets of three and projecting through the first upward reach of 120 the rear wall of a hopper.

In Fig. 10 a vibratory bar 53 is shown in the same upward reach of the rear wall, said bar having teeth 54 beveled forwardly from a straight back wall.

- 5 In Fig. 11 a modified form of drive is shown and in this a driven shaft 55 is journaled parallel to the succession of hoppers and is driven by the motor 56, to which it is connected by the pulleys 57 and 58 and belt 59. The bevel gears 60 are mounted on the shaft 55 and coact with the bevel gears 61 which are mounted at the outer ends of the transverse cam shafts 62 and by this arrangement the cams may be maintained 10 constantly in alternative operating positions, thereby materially reducing the load on the motor.

In Fig. 12 the rear wall is shown in three reaches, 63, 64 and 65 and in this construction it will be seen that a greater slope is given to the upper reach 65 than to the middle reach 64, consequently a small log cannot force a larger log back into the hopper, thereby leaving the latter crowded with 25 large logs, because the center vertical line through the small log 66 is on the hopper side as compared with the center vertical line through the larger log 67, which insures a constant push by the small log on 30 the bigger log in the direction of the dividing platform or wall from the next hopper in succession.

This mechanism is merely shown diagrammatically in the drawings and only briefly 35 described, as it is not an essential feature in the invention.

The operation of the invention may be facilitated by relieving the hoppers of finished logs before reaching the delivery end 40 and by doing this the efficiency may be greatly increased as smooth logs will not then interfere by delaying the contact of the bark covered logs with one another.

Various changes may be made in the construction of the machine without departing 45 from the spirit of the invention, so long as said changes are within the scope of the claims for novelty following.

What I claim is:—

- 50 1. In a log barker and the like, a hopper having front and rear walls terminating in a slotted bottom portion and a driven rotatory member suitably journaled and in rotation entering the hopper through said 55 slotted bottom portion and operating toward the rear wall.

2. In a log barker and the like, a hopper having front and rear walls terminating in a slotted bottom portion and a driven oscillatory member projecting through the slotted bottom and engaging the logs to keep 60 them in a constant circulatory movement.

3. In a log barker and the like, a hopper having an opening at the lower rear end 65 thereof, a driven shaft journaled adjacent

to said opening, and a cam shaped member fixedly mounted on said shaft and entering said opening at each half revolution, and rolling the logs in contact therewith.

4. In a log barker and the like, a hopper 70 having a plurality of openings at the lower rear end, a shaft suitably driven, and journaled adjacent to said opening, and cams mounted on said shaft and having log rolling faces receding from the direction of rotation 75 and corresponding recesses on the inner sides, said cams entering said openings and engaging the logs in said hopper.

5. In a log barker and the like, a hopper having openings at the lower end of the rear 80 wall in the bottom thereof, a water sprinkling device thereabove, and disturbing elements entering said openings and engaging the logs and creating a constant rolling movement and establishing a circulation of 85 the logs in the hopper.

6. In a log barker and the like, a stationary hopper having a plurality of openings in the bottom, shaft bearings, a cam shaft journaled in said bearings and extending 90 across the outside of said hopper adjacent to said openings, a gear on said shaft, a pinion coacting with said gear, a pulley and belt connection to said pinion shaft, a motor driving said pulleys, and a plurality of 95 cams on said cam shaft engaging the logs in the hopper and rolling the same at each operation.

7. In a log barker and the like, a plurality of hoppers having openings in the bottoms 100 at the lower end of the rear wall, disturbing elements entering said openings periodically and creating a regular and constant movement of the logs for rubbing purposes, a feeding platform, a sprinkling device over 105 each hopper, connecting platforms between the several hoppers, and a runway from the last hopper.

8. In a log barker and the like, a succession of hoppers having openings in the bottoms 110 at the lower ends of the rear walls, a driven shaft suitably journaled alongside said hoppers, transverse shafts suitably journaled and extending across said openings, bevel gear connecting said driven and 115 transverse shafts, a motor operatively connected with said driven shaft, and cams mounted on said transverse shafts in alternately operating positions respectively and in rotation entering said openings and engaging the logs.

9. In a log barker and the like, a hopper having a front sloping downwardly to the rear wall, the latter being formed in lower, middle and upper reaches, said upper reach having a greater inclination than said middle reach to facilitate the delivery of larger logs, and side walls closing in said front and rear walls, and means for agitating said logs.

10. In a log barker and the like, a hopper having an opening in the bottom at the lower end of the rear side forming flushing and cam slots, rotating cams extending 5 through said slots for disturbing said logs at short intervals and automatic means for receiving and discharging the bark removed from the logs free of the accompanying water.
- 10 11. In a log barker and the like, a hopper having front and rear walls and a bottom connecting the front and rear walls and provided with a single continuous slot extending across the central portions of the bottom, 15 and a driven rotary member suitably journaled and in rotation entering and leaving the hopper through the said single slot and operating toward the rear wall.
- 20 12. In a log barker and the like, a hopper having front and rear walls and a bottom connecting the front and rear walls and provided with a single continuous slot extending across the bottom from front to rear, and a driven rotary member suitably 25 journaled and in rotation entering and leaving the hopper through said single slot and operating toward the rear wall.
- 30 13. In a log barker and the like, a hopper having front and rear walls provided with inclined portions forming a continuous bottom for the hopper and provided with registering slots forming a single continuous
- opening extending across the bottom of the hopper from front to rear, and a driven rotary member suitably journaled and in rotation entering and leaving the hopper through said single opening in the bottom 35 of the hopper and operating toward the rear walls.
14. In a log barker and the like, a hopper 40 having a curved sloping front wall and a rear wall having upper and lower inclined portions, the lower portion of the rear wall having a greater inclination than the upper portion thereof and the lower portions of 45 the front and rear walls meeting and constituting a continuous bottom for the hopper and provided with registering slots forming a single continuous opening extending across the bottom from front to rear, and a driven 50 rotary member suitably journaled and in rotation entering and leaving the hopper through said single opening and operating toward the rear wall.
15. In a log barker and the like, a stationary hopper receiving logs for circulatory and rubbing movement in direct contact with its own bottom and means for effecting a 55 rolling and rubbing movement of the logs within the hopper.

In witness whereof I have hereunto affixed my signature.

CARL BUSCH THORNE.
